INVENTOR.

UNITED STATES PATENT OFFICE.

HIRAM H. SPONENBURG, OF GURNEE, ILLINOIS, ASSIGNOR TO OTTO R. BARNETT, OF CHICAGO, ILLINOIS.

RAIL-ANCHOR.

1,177,731.

Specification of Letters Patent. Patented Apr. 4, 1916.

Application filed August 16, 1915. Serial No. 45,719.

To all whom it may concern:

Be it known that I, HIRAM H. SPONENBURG, a citizen of the United States, residing at Gurnee, in the county of Lake and State of Illinois, have invented certain new and useful Improvements in Rail-Anchors, of which the following is a specification.

My invention relates to a device for preventing the longitudinal creep of railway rails, devices of this sort being commonly called rail anchors, rail stays or anti-creepers, and the principal object of the invention is to provide a rail anchor with novel and more efficient means than has been heretofore employed for maintaining the grip of the device on the rail as against disturbing influences such as the vibration of the rail, differences in expansion and contraction of metals due to temperature changes, and the tendency of rails to re-act in a direction reverse to the direction of travel after the forward impulse has ceased.

The invention has for a further object to provide a rail anchor comprising a yoke adapted to extend around the base of the rail and wedging means driven in between the yoke and the edge of the rail consisting of rigid and flexible members, the latter being put under stress against the edge of the rail and formed so as to take a firm hold upon the rail, thereby preventing any retrograde movement of the wedging means.

The invention has for further objects such other new and improved constructions, arrangements and devices relating to devices for preventing the longitudinal creep of railroads rails as will be hereinafter described and claimed.

The invention is illustrated, in a preferred embodiment, in the accompanying drawings wherein—

Figure 1 is a side elevation of a rail anchor constructed in accordance with the principles of my invention illustrated as applied to the rail, the latter being in section. Fig. 2 is a plan view of the parts shown in Fig. 1. Fig. 3 is a sectional plan taken on line 3—3 of Fig. 1. Fig. 4 is a cross sectional view on line 4—4 of Fig. 2. Figs. 5 and 6 are views, in perspective, of the two members which together constitute the wedging means intervening between the body of the anchor or yoke member and the rail. Fig. 7 is a view similar to Fig. 1 showing a modified construction, and Fig. 8

is a plan view of the device shown in Fig. 7 with certain parts in section.

Like characters of reference designate like parts in the several figures of the drawings.

Referring first to Figs. 1 to 6 inclusive, A is the rail and B one of the cross ties on which the rail is supported.

The rail anchor, in the embodiment of my invention shown in these figures, consists of a yoke member C formed at one end with a jaw D adapted to engage one edge of the base flange of rail A and at the other end with a larger jaw E. At this end of the yoke there is a tie abutting flange F which bears against the side face of the tie B. The other end of the yoke preferably stands a little away from the tie for the purpose of obtaining the cramping action by which a forward creeping tendency is self-checked, which is familiar in devices of this sort.

The yoke C consists preferably, though not necessarily, of a single integral malleable casting of sufficient size and suitably ribbed to withstand the very severe stresses which are exerted against a rail anchor in service.

G (Fig. 6) is a rigid wedge member arranged within jaw E and provided preferably with a projecting part H which overlaps the base flange of the rail. J (Fig. 5) is a flexible member slightly curved which intervenes between the wedge G and the adjacent edge of the base flange of the rail and is preferably provided at one extremity with a somewhat sharp cutting edge K which bites into the edge of the rail. At the other extremity the member J is formed with a projection or hook L which extends around the end of wedge G.

The wedging means, consisting of members G, J, is driven into jaw E so as to put member J under bending stress by striking on the large end of wedge member G. The member J, because of its flexibility, tends to absorb vibration so as to prevent the wedging means from backing out of the jaw of the yoke. Retrograde movement of the wedging means is also checked by the fact that the cutting edge J will bite into the edge of the rail, as indicated in Fig. 2. It will be seen that the member J, originally slightly curved, is bent out by being driven with the wedge into J, E, so that for a considerable portion of its length it lies along and against the edge of the rail base, provid-

ing with the wedge a rigid and positive means for holding the yoke on the rail.

A modified construction is shown in Figs. 7 and 8. The flexible member J' , which, as in the other construction, preferably intervenes between the base of the rail and the wedge member designated G' is straight for most of its length, instead of being curved as is the case with the flexible member J . The 10 extremity, however, of the member J' is curved as indicated at J'' , the dotted lines (Fig. 8) indicating the contour of the end of the flexible member before being put under bending stress, and the full lines the position which the curved end of said member assumes when the rail anchor is in operative position on the rail. The wedging means G', J' may be driven into the jaw E' of yoke member C' by striking on the thicker 20 end of wedge member G' .

While I have described my invention in certain preferred embodiments, further modifications, I apprehend, might be made without departure from the principles of 25 the invention. Therefore I do not wish to be understood as limiting the invention to the exact constructions and arrangements shown and described except so far as the claims are specifically so limited.

30 I claim:

1. In a rail anchor, the combination of a yoke element adapted to extend around the base of a rail, and wedging means which intervenes between the yoke and the rail comprising a rigid member and a flexible member provided at one extremity with a biting edge.

2. In a rail anchor, the combination of a yoke element adapted to extend around the 40 base of a rail, and wedging means which intervenes between the yoke and the rail comprising a rigid member and a flexible member provided at one extremity with a biting edge and at the other with means engaging 45 said element with the rigid element.

3. In a rail anchor, the combination of a yoke element adapted to extend around the base of a rail, and wedging means which intervenes between the yoke and the rail comprising a rigid member and a flexible member provided at one extremity with a biting edge and at the other with means engaging 50 said flexible member with the rigid member.

4. In a rail anchor, the combination of a yoke element adapted to extend around the base of a rail, and wedging means which intervenes between the yoke and the rail comprising a rigid member and a flexible member provided at one extremity with a biting 55 edge adapted to engage the edge of the rail base, and at the other with means for engaging said flexible member with the rigid member.

5. In a rail anchor, the combination of a 60 yoke element adapted to extend around the

base flange of a rail, and wedging means which intervenes between the yoke and rail comprising a flexible member which bears against the rail and a rigid member between the flexible member and the yoke. 70

6. In a rail anchor, the combination of a yoke element adapted to extend around the base flange of a rail, and wedging means which intervenes between the yoke and rail comprising a flexible member which bears against the rail and is provided with a biting edge at one extremity, and a rigid member 75 between the flexible member and the yoke.

7. In a rail anchor, the combination of a yoke element adapted to extend around the base flange of a rail, wedging means which intervenes between the yoke and rail comprising a flexible member which bears against the rail and is provided with a biting 80 edge at one extremity, and a rigid member between the flexible member and the yoke, and means engaging the flexible member with said rigid member.

8. In a rail anchor, the combination of a yoke element adapted to extend around the base flange of a rail, and wedging means which intervenes between the yoke and the rail comprising a rigid member and a flexible member which has a projection at one 90 end extending around the end of the rigid member.

9. In a rail anchor, the combination of a yoke element adapted to extend around the base flange of a rail, and wedging means which intervenes between the yoke and the rail comprising a rigid member and a flexible member bearing against the rail which has a projection at one end extending around the end of said rigid member. 10

10. In a rail anchor, the combination of a yoke element adapted to extend around the base flange of a rail, and wedging means which intervenes between the yoke and the rail comprising a rigid member and a flexible member bearing against the rail which has a projection at one end extending around the end of said rigid member and a biting edge at the other end adapted to bear against 11 the rail.

11. In a rail anchor, the combination of a yoke element adapted to extend around the base flange of a rail, a rigid wedge, and a flexible member which intervenes between the wedge and the rail. 1

12. In a rail anchor, the combination of a yoke element adapted to extend around the base flange of a rail, a rigid wedge, and a flexible member which intervenes between the wedge and the rail and has a biting 1 edge bearing against the rail.

13. In a rail anchor, the combination of a yoke element adapted to extend around the base flange of a rail, a rigid wedge, and a flexible member which intervenes between 1

the wedge and the rail and has a biting edge at one end which bears upon the rail, and a projection at the other extending around one end of the wedge.

- 5 14. In a rail anchor, the combination of a yoke element adapted to extend around the base flange of a rail, a rigid wedge, and a flexible member which intervenes between the wedge and the rail and has a projection 10 which extends around one end of the wedge.

15. In a rail anchor, the combination of a yoke element which is adapted to extend around the base flange of a rail and is provided with a tie abutting flange, and wedging means adapted to be driven between the 15 yoke and the rail comprising a rigid member and a flexible member, the latter of which is put under stress against the rail.

16. In a rail anchor, the combination of 20 a yoke element which is adapted to extend around the base flange of a rail and is provided with a tie abutting flange, and wedging means adapted to be driven between the yoke and the rail comprising a rigid member 25 and a flexible member, the latter of which is put under stress against the rail and is provided with a biting edge adapted to bite into the rail.

17. In a rail anchor, the combination of 30 a yoke element which is adapted to extend around the base flange of a rail and is provided with a tie abutting flange, and wedging means adapted to be driven between the yoke and the rail comprising a rigid member 35 and a flexible member, the latter of which is put under stress against the rail and is provided with a biting edge adapted to bite into the rail and with means engaging it with said rigid member so that said 40 members move together when the rigid member is driven in place.

18. In a rail anchor, the combination of a yoke element which is adapted to extend 45 around the base flange of a rail and is provided with a tie abutting flange, and wedging means adapted to be driven between the yoke and the rail comprising a rigid member and a flexible member, the latter of which is formed at one end with a biting 50 edge engaging the rail and at the other end with a projection which extends around the end of the wedge.

19. In a rail anchor, the combination of

an integral yoke member formed at one end with a jaw adapted to engage one edge of 55 the base flange of a rail and at the other end with a larger jaw having an interior wedge face, a wedge adapted to be driven into said last mentioned jaw, and a curved spring member which intervenes between 60 said wedge and the edge of the rail.

20. In a rail anchor, the combination of an integral yoke member formed at one end with a jaw adapted to engage one edge of 65 the base flange of a rail and at the other end with a larger jaw having an interior wedge face, a wedge adapted to be driven into said last mentioned jaw, and a curved spring member which intervenes between 70 said wedge and the edge of the rail and is formed at one end with a biting edge adapted to engage the edge of the rail base and at the other with a projection which extends around the end of said wedge.

21. In combination, a rail and a rail anchor comprising rail gripping means and a flexible, slightly bowed strip of metal, one end of which is held in rigid, clamped relation with the rail gripping means and rail, the other end being out of contact with one 80 of said last two mentioned elements except at its extremity which bears resiliently against said element.

22. In combination, a rail and a rail anchor comprising rail gripping means and a 85 flexible, slightly bowed strip of metal, one end of which is held in rigid clamped relation with the rail gripping means and rail, the other end being out of contact with one of said last two mentioned elements except 90 at its extremity which is provided with a biting edge bearing resiliently against said element.

23. In combination, a rail and a rail anchor comprising rail gripping means and a 95 flexible, slightly bowed strip of metal, one end of which is held in rigid, clamped relation with the rail gripping means and rail, the other end being out of contact with one of said last two mentioned elements except 100 at its extremity which is provided with a biting edge bearing resiliently against said element, the other extremity of the strip being provided with a lateral extension to engage said rail gripping means.

HIRAM H. SPONENBURG.
